United States Patent Office.

JOHN H. CRAWFORD AND WILLIAM H. CRAWFORD, OF OSHKOSH,
WISCONSIN.

Letters Patent No. 85,911, dated January 19, 1869.

IMPROVED MACHINE FOR CUTTING SHINGLE-BANDS.

The Schedule referred to in these Letters Patent and making part of the same.

To all whom it may concern:

Be it known that we, JOHN H. CRAWFORD and WILLIAM H. CRAWFORD, of the city of Oshkosh, county of Winnebago, and State of Wisconsin, have invented a new and useful Machine for Cutting Shingle-Bands; and we do hereby declare that the following is a full and exact description thereof, reference being had to the accompanying drawings, and to the letters of reference marked thereon, making a part of this specification.

Similar letters of reference indicate corresponding parts in the several figures.

Figure 1 is a plane view of the machine.

Figure 2 is a longitudinal section taken in a vertical plane.

Figure 3 is an enlarged transverse section taken in a vertical plane, indicated by the line *m k*, fig. 1.

Figure 4 is an enlarged perspective view of *g o*, fig. 2.

Figure 5 is an enlarged perspective view of *f*, fig. 2.

Our invention relates to machinery for cutting and punching metallic strips from sheet-metal. The strips are used (in combination with wooden binders) in packing bunches of shingles, and other packages of a similar character.

The nature of our invention consists in combining revolving cutters and a stationary cutter with rollers adapted to effect an automatic feed, and device for punching, the rollers on one side of the sheet-metal being provided with annular grooves, and the rollers on the opposite side being provided with sprigs or punches, at regular intervals, that correspond with the grooves.

The sheet-metal, as it passes between the rollers, is first punched, and then carried forward to the cutters with uniform feed and cut, one with another, of a uniform width.

To enable others skilled in the art to understand our invention, we will proceed to describe our machine.

In the accompanying drawings—

A represents a rectangular frame, which is adapted for containing and supporting the several parts for feeding, punching, and cutting the bands.

B is a feed-table.

b is an adjustable guide.

c c are rollers, with annular grooves.

c c and *d d* are rollers, provided with punches, *d*, at regular intervals on their outer periphery, corresponding to the annular grooves in *c c*.

e is a revolving cutter-head, with a length equal to the longest band desired to be cut, and is provided with two cutters, or with any other number of cutters deemed desirable.

f is a cutter, an enlarged view of which is seen in fig. 5, corresponding in length to the cutters on *e*.

The cutter *f* is secured to the front edge of the table *B*, and is adjusted vertically by set-screw at *n*, fig. 2.

g g are guides, suspended from a bar, *o*, that hold the sheet-metal down to the table, and to the stationary cutter *f*, an enlarged view of which is seen in fig. 4.

h is a pulley, and gives a rotary motion to the cutter-head *e*.

i j k l m are gear-wheels that operate the feed and punching-rollers, and effect the relations of the latter to the cutters; *k*, in fig. 1, being represented in section.

The guide *b* being adjusted to the length of band desired, and the sheet-metal being cut of such width as would be desired for the length of band, the sheet-metal is placed on the table *B*, touching the guide *b*. Power being applied to the pulley *h*, the cutter-head, and feed, and punches are set in motion, the sheet-metal is caught between the rollers *c* and *d*, punched at regular intervals, then carried forward to the rotating cutter *e* and stationary cutter *f*, and cut of a uniform width, and is thus completed, and delivered ready for use.

What we claim as our invention, and desire to secure by Letters Patent, is—

The rollers *c c* and *d d*, constructed and arranged relatively to each other, and to the table *B* and cutters *e* and *f*, substantially as described, for the purposes set forth.

JOHN H. CRAWFORD.

WILLIAM H. CRAWFORD.
